UNITED STATES PATENT OFFICE.

HARRY R. NOFTZ, OF TOLEDO, OHIO, ASSIGNOR TO THE NATIONAL SUPPLY COMPANY,
OF TOLEDO, OHIO, A CORPORATION OF OHIO.

ROTARY EARTH DRILLING AND BORING MACHINE.

1,119,446.

Specification of Letters Patent.

Patented Dec. 1, 1914.

Application filed July 30, 1913. Serial No. 781,950.

To all whom it may concern:

Be it known that I, HARRY R. Nortz, a citizen of the United States, residing at Toledo, in the county of Lucas and State of Ohio, have invented new and useful Improvements in Rotary Earth Drilling and Boring Machines, of which the following is a specification.

My invention relates generally to rotary drilling machines for the formation of gas wells, oil wells, and the like, but more specifically it relates to improvements whereby the carriers for the pipe-gripping jaws may be drawn nearer together or farther apart without it being necessary to maintain the carriers in a parallel relation to each other. I accomplish this by improvements in the swiveling devices.

Referring to the accompanying drawings, Figure 1 is a plan of a rotary table equipped with my invention; Fig. 2, a side elevation of Fig. 1, with parts in section; Fig. 3, a vertical section through one of the swiveling devices; and Fig. 4, a side view of one of the swivel nuts or sleeves. Fig. 5 is a horizontal section of the left-hand side of Fig. 2 on the level of the pin 24. Fig. 6 is a side elevation of the swivel-block section 17, Fig. 2. Fig. 7 is an elevation of the block 17 looking to the left, Fig. 6. Fig. 8 is a horizontal section through the swivel-bearing 14, Fig. 3. Fig. 9 is a side elevation of the central portion of one of the screws 5, the bearing 5' and the locking block 8^a being in vertical section.

On the drawings, 1 is a rotary horizontal table driven by the bevel gearing 2 and supported on rollers (one marked 3 being shown) supported by the base 4.

The parallel screws 5 are supported at opposite sides of the center of the table 1 in the bearings 5' supported by the table, the screws being prevented from moving lengthwise by means of the collars 6 engaging one face of the bearings 5' and the polygonal sections 7 engaging the opposite face of the bearings 5', the collars and polygonal sections being larger than the bearing portion 8 of the screws. One end of each screw has right-hand threads and the other left-hand threads. The outer ends of the screws have polygonal portions 5^a so that a wrench or crank can be applied thereto to turn them. The polygonal sections 7 are engaged by the blocks 8 secured to the

top of the bearings 5' by the bolts 8^b to prevent the turning of the screws.

At right angles to the screws 5, I arrange the two bars or carriers 9 for the roller grips 10, one bar being at each side of the center of the table, each carrying a pair of grips arranged to engage the sides of the pipe 11 in a well-known manner.

The ends of the carriers are all constructed alike so that a description of one will suffice for a description of all. On Fig. 3, I show the end of one carrier 9. The said end is provided with a pair of horizontal projections or extensions 12 and 13, one continuous with the upper part of the carrier, 70 and the other with the lower part thereof, whereby a considerable space is left between the projections 12 and 13 for the swivel devices. The lower face of the projection 12 is provided with the short vertical cylindrical swivel-bearing 14 and the upper face of the projection 13 is provided with the short vertical cylindrical swivel-bearing 15, the bearings 14 and 15 being in vertical alinement.

A swivel block 16, divided into lateral halves 17 and 18 by a plane at right-angles to the screws 5, has at its ends recesses 19 to receive the bearings 14 and 15 and constitute bearing boxes therefor. The block 85 16 has a round horizontal opening 20 therein to receive the body of the sleeve-nut 21, having the flange 22 bearing against the outer face of the section 17 and provided with notches 23 to receive the spring-actuated pin 24 in the section 17, the said pin locking the sleeve-nut in any selected axial adjustment thereof. The inner end of the sleeve-nut 21 is provided with the washer 25 which rests against the outer face of the section 18, the nut 26 being screwed on the threads 27 on the end of the sleeve-nut and against the washer 25. The outer end of the sleeve-nut 21 is provided with a squared portion 28 by which it may be rotated.

The sleeve-nuts 21 are all internally threaded and work on the threads of the screws 5 which extend through them. These sleeve-nuts have several oil-holes 29 which receive oil from the ducts 30 in the sections 105 17 and 18 and convey it to the screws 5.

It is seen that, if one of the screws 5 is rotated, two of the ends of the carriers 9 will be brought toward or away from each other without its being necessary to turn the 110

other screw 5 at the same time or at the same speed.

I claim—

1. In a rotary drilling machine, a rotary table, a pair of grip ring carriers thereon, and a pair of screws for moving the carriers toward and away from each other, each end of each carrier having a pair of horizontal extensions, cylindrical bearings on the opposing faces of each pair of extensions; a swivel-block having end recesses to receive the said cylindrical bearings and divided into lateral sections, and a horizontal sleeve-nut rotatable in each swivel-block and on each end of each screw.
2. In a rotary drilling machine, a rotary table, a pair of grip ring carriers thereon, and a pair of screws for moving the carriers toward and away from each other, each end of each carrier having a pair of horizontal extensions, cylindrical bearings on the opposing faces of each pair of extensions, a swivel-block having end recesses to receive the said cylindrical bearings and divided into lateral sections, a horizontal sleeve-nut rotatable in each swivel-block and on each end of each screw, and means for holding the sleeve-nut in the swivel-block and for holding the sections of the swivel-block in place.
3. In a rotary drilling machine, a rotary table, a pair of grip ring carriers thereon, and a pair of screws for moving the carriers toward and away from each other, each end

of each carrier having a pair of horizontal extensions, cylindrical bearings on the opposing faces of each pair of extensions, a swivel-block having end recesses to receive the said cylindrical bearings and divided into lateral sections, a horizontal sleeve-nut rotatable in each swivel-block and on each end of each screw, a notched flange on the sleeve-nut bearing on the swivel-block, and means for engaging one of the notches and preventing the rotation of the sleeve-nut.

4. In a rotary drilling machine, a rotary table, a pair of grip ring carriers thereon, and a pair of screws for moving the carriers toward and away from each other, each end of each carrier having a pair of horizontal extensions, cylindrical bearings on the opposing faces of each pair of extensions, a swivel-block having end recesses to receive the said cylindrical bearings and divided into lateral sections, a horizontal sleeve-nut rotatable in each swivel-block and on each end of each screw, a notched flange on the sleeve-nut bearing on the swivel-block, and a spring-pin for engaging one of the notches and preventing the rotation of the sleeve-nut.

Signed at Toledo, Ohio, this 24 day of July, A. D. 1913.

HARRY R. NOFTZ.
